CELLULAR SUPPORT FOR LOUDSPEAKERS,
INCLUDING ACOUSTIC CHAMBERS

Gabriel M. Giannini, North Hollywood, Calif., assignor, by mesne assignments, to Automatic Electric Laboratories, Inc., a corporation of Delaware

Application December 3, 1942, Serial No. 467,695

2 Claims. (Cl. 181—31)

1

The present invention relates to sound translating devices and to methods of making the same. This application is a continuation-in-part of the copending application of Gabriel M. Giannini, Serial No. 419,165, filed November 14, 1941, now Patent No. 2,341,539, granted February 15, 1944.

Heretofore it has been proposed to provide a sound translating device comprising an outer shell formed of metal or the like, an electromagnetic unit housed and rigidly supported by the shell in spaced relation with respect thereto, and a layer of fibrous material interposed between the shell and the unit and constituting a cellular filler for the space therebetween, whereby the cellular chamber thus formed effects a desired influence upon the vibrating diaphragm of the unit.

While a sound translating device of this character is reasonably satisfactory in service, it embodies certain objectionable features in that it is extremely difficult accurately to control the effective or average density of the cellular chamber and its consequent influence upon the diaphragm of the electromagnetic unit. Also the unit is rigidly connected mechanically to the outer shell and consequently to the external support which results in the transmission of vibrations and noises between the unit and the external support, whereby the diaphragm of the unit is adversely influenced, causing distortion in the response thereof.

Accordingly, it is an object of the present invention to provide a sound translating device comprising a chamber formed of cellular material housing and resiliently supporting the electromagnetic unit and provided with an outer shell substantially impervious to air, wherein the shell and the unit cooperate to define a cellular chamber housing the casing, the cellular chamber communicating with the vibratory diaphragm of the unit in order to influence the response thereof.

Another object of the invention is to provide a sound translating device comprising a casing of the general character noted; wherein the casing is formed of a plurality of sections of cellular material of different densities, whereby a corresponding plurality of cellular chambers are provided which communicate with the vibratory diaphragm of the unit in order mutually to influence the response thereof.

Another object of the invention is to provide a sound translating device comprising a cover formed of cellular material, and provided with

2

an outer shell substantially impervious to air, wherein the shell cooperates with the diaphragm of the electromagnetic unit to define a cellular chamber housing the cover, the shell and the cover having communicating openings formed therein providing a sound passage connecting the diaphragm and the outside air, whereby the cellular chamber influences the response of the diaphragm.

10 A further object of the invention is to provide a hollow self-supporting casing adapted to receive and resiliently to support the electromagnetic unit of a sound translating device, wherein the casing comprises wall structure molded of cellular material and an outer coating providing a shell substantially impervious to air.

15 A still further object of the invention is to provide an improved method of making a hollow casing of the character noted for receiving and 20 for resiliently supporting the electromagnetic unit of a sound translating device.

The invention, both as to its organization and method of operation, together with further objects and advantages thereof, will best be understood by reference to the following specification taken in connection with the accompanying drawings, in which Figure 1 is a longitudinal sectional view of a sound translating device embodying the present invention; Fig. 2 is an exploded view, 25 partly broken away, of the electromagnetic unit incorporated in the device shown in Fig. 1; Fig. 3 is an enlarged fragmentary sectional view of the upper portion of the unit shown in Figs. 1 and 2; Fig. 4 is an enlarged longitudinal sectional view 30 of a modified form of the diaphragm mounting of the unit shown in Figs. 1 to 3, inclusive; Fig. 5 is a longitudinal sectional view of a cover casting member which may be secured to the open top of the body casing member of the device 35 shown in Fig. 1; and Fig. 6 is a longitudinal sectional view of a modified form of the sound translating device embodying the present invention.

Referring now more particularly to Figs. 1 to 5, inclusive, of the drawings, the sound translating 40 device there shown is of the electrodynamic type and comprises a self-contained electromagnetic unit 10. The unit 10 includes a permanently magnetized annular ring 100 formed of Alnico or the like, a bottom plate 101, a cylindrical center pole piece 102 and a top plate 103. Preferably, the parts 101, 102 and 103 are formed of Allegheny Electric Metal or other high permeable magnetic material. The center pole piece 102 is provided with a lower portion 102a of reduced diameter 45 which extends within a centrally disposed

circular opening provided in the bottom plate 101. A sweat connection between the side walls of this opening and the side walls of the lower portion 102a is used rigidly to secure the center pole piece 102 to the bottom plate 101. At its upper end the center pole piece 102 is provided with a portion 102b of reduced diameter which extends within a centrally disposed circular opening 103a formed in the top plate 103. As best shown in Fig. 1 of the drawings, the diameter of the opening 103a is somewhat larger than the diameter of the upper portion 102b of the center pole piece 102; and the upper end of the center pole piece 102 is concentrically disposed within the opening 103a, whereby an annular air gap is formed between the adjacent side walls of the opening 103a and the upper portion 102b of the center pole piece 102. The magnetic circuit of the unit 10 is completed by means of three clamping screws 104 which extend through openings provided in the bottom plate 101 and are threaded into tapped holes 127 provided in the top plate 103. The screws 104 serve rigidly to clamp the annular permanent magnet 100 between the top and bottom plates 103 and 101.

The moving system of the unit 10 comprises a cone-shaped diaphragm 105 which is formed of pressed fiber and is carried by a supporting structure which comprises a bottom ring 106, six spacing collars 107, a pair of clamping rings 108 and 109, two paper washers 110 and 111 and six assembly screws 112. The character of the diaphragm 105 depends upon whether the device is to be utilized as a transmitting element or as a receiving element. In the event the device is to be utilized as a transmitting element or transmitter, the diaphragm 105 is of one-piece construction and is provided with an outer flat annular ring portion 105a which extends between and is cemented to the paper washers 110 and 111 and is uniformly clamped around its periphery between the washers 110 and 111 by the two clamping rings 108 and 109. On the other hand, in the event the device is to be used as a receiving element or receiver, the diaphragm construction illustrated in Fig. 4 of the drawings is used. In this construction only the bulbous portion of the diaphragm 105 is constructed of molded or pressed fiber, the periphery of the diaphragm 105 being secured to an annular ring 105b formed of treated silk which is disposed between and cemented to the paper washers 110a and 111a. The purpose of this arrangement illustrated in Fig. 4 of the drawings is to permit substantially free vibration of the diaphragm 105, particularly at the low frequencies of the operating frequency range, whereby the response of the device as a receiver is enhanced at these frequencies. On the other hand, when the one-piece diaphragm arrangement illustrated in Figs. 1 to 3, inclusive, of the drawings is used, the diaphragm 105 is considerably stiffer and, accordingly, the response thereof, particularly low frequencies, is substantially less than when the diaphragm construction illustrated in Fig. 4 is used. By virtue of this increased stiffness of the one-piece diaphragm arrangement illustrated in Figs. 1 to 3, inclusive of the drawings, low frequency noise components of sound are prevented from producing any substantial response of the device.

A moving coil 113 is cemented to the lower bulbous portion of the diaphragm 105 and is concentrically disposed within the air gap defined by the upper portion 102b of the pole piece 102

and the opening 103a provided in the top plate 103. The terminal ends of this coil may be electrically connected to lead-in wires in any desired manner, although, preferably, the connections are made at anchor posts which extend through and are secured to the lower portion of the diaphragm 105. In order to preserve the correct lateral and axial spacing of the moving coil 113 in the air gap of the magnetic circuit and to provide additional support to the diaphragm 105, a string supporting arrangement is provided. This arrangement comprises three connected strings 114a, 114b and 114c which extend through equiangularly spaced openings cut through the lower portion of the diaphragm 105 and are joined together, as indicated at 114d, within the dished cavity of the diaphragm 105. The free ends of the three strings are respectively anchored by clamping them to the lugs 115a, 115b, not shown, and 115c which extend radially inward and are turned upward from the supporting ring 106. Small clamping plates 116a, 116b, not shown, and 116c disposed between shortened spacing collars 107 are used to clamp the free ends of the strings 114a, 114b and 114c against the lugs 115a, 115b and 115c. Preferably, the three strings 114a, 114b and 114c are formed of silk fishline or the like and it will be understood that by appropriately tensioning the three strings the required support for the moving coil 113 may be obtained.

In order to seal the annular cavity 128 formed between the spaced-apart annular permanent magnet 100 and the center pole piece 102 from the acoustical cavity 117 formed adjacent the lower side of the diaphragm 105, a sealing ring 118 is provided which snugly encloses the upper end portion 102b of the center pole piece 102 and is clamped to the under side of the top plate 103 by means of assembly screws 119. Preferably, the sealing ring 118 is formed of rubber, molded Bakelite or other insulating material having nonmagnetic properties. This sealing arrangement, including the sealing ring 118, prevents the first-mentioned annular cavity, formed between the annular permanent magnet 100 and the center pole piece 102, from communicating with the acoustical cavity 117 provided adjacent the lower side of the diaphragm 105, thereby to reduce the effective volume of the acoustical cavity 117 and consequently to enhance the stiffness thereof, whereby the damping action exerted upon the diaphragm 105 is enhanced.

In the assembly of the unit 10 the magnetic circuit structure is built by first securing the sealing ring 118 to the under side of the top plate 103 and then setting the assembly screws 104 to clamp the annular permanent magnet 100 between the top and bottom plates 103 and 101. After the magnetic structure is thus assembled the portion of the sealing ring 118 facing toward the air gap of the structure may be painted with shellac or other sealing compound to provide an acoustical seal which blocks off the annular cavity, formed between the annular permanent magnet 100 and the center pole piece 102, from the acoustical cavity 117 adjacent the under side of the diaphragm 105. The diaphragm assembly is prepared by cementing the two paper washers 110 and 111 to the top and bottom surfaces of the flat annular portion 105a of the diaphragm 105, assuming that a transmitter is being constructed, and by cementing the moving coil 113 to the lower central portion of the diaphragm 105. If the device is to be used as a receiver, the dia-

phragm structure illustrated in Fig. 4 of the drawings is constructed by first cementing the paper washers 110 and 111 to the opposite peripheral surfaces of the silk ring 105b, after which the inner upper edge surfaces of the silk ring 105b are cemented to the under side of the diaphragm 105. Following the assembly of the diaphragm structure the three strings 114a, 114b and 114c are drawn through the angularly spaced openings provided in the base of the diaphragm 105. After this operation is performed the supporting ring 106, the clamping rings 108 and 109 and the assembled diaphragm structure may be stacked on the top plate 103 and the assembly screws 112 may successively be inserted through the registering openings provided in the stacked clamping rings and diaphragm structure, the spacing collars 107 and the supporting ring 106. Initially the screws which extend through the clamping elements 116a, 116b and 116c are not tightened but the alternate assembly screws which extend only through alternate spacing collars 107 are tightened sufficiently to provide a semirigid assembly. Following this operation, the ends of the strings 114a, 114b and 114c may be threaded between the clamping elements 116a, 116b and 116c and their associated lugs 115a, 115b and 115c and properly tensioned to provide the required lateral axial support for the diaphragm 105. Thereafter the assembly screws 112 may be tightened securely to clamp the ends of the strings 114a, 114b and 114c between the clamping elements 116a, 116b and 116c and their respective associated lugs 115a, 115b and 115c. Thus the structure of the electromagnetic unit 10 is completed.

Also the sound translating device comprises a body casing member 11 having the form of a hollow block of acoustical insulating material 120; the electromagnetic unit 10 being arranged and snugly received within the opening formed in the hollow block 120. Preferably, the hollow block 120 is formed by a molding process described more fully hereinafter and consists principally of a fibrous insulating material and a suitable binder; whereby the molded acoustical block 120 is of cellular construction and is somewhat porous so that air can be transmitted therethrough. The outer surfaces of the molded block 120 including the bottom wall and the connected side wall are provided with one or more coats of lacquer or paint 125 in order to minimize or substantially to exclude the transmission of sound therethrough. In the illustrated embodiment shown in Fig. 1 of the drawings, the molded block 120 may be either round or square in transverse cross-section and is provided with a cylindrical opening therein which snugly receives the side walls of the electromagnetic unit 10, as previously noted. In the event the sound translating device is to operate as a nondirectional device, the assembly is completed by closing the open top of the hollow block 120 with a silk screen 123 having approximately the characteristic impedance of air over which is placed a thin sheet of aluminum 124 having a number of holes of appropriate size cut therethrough for the purpose of transmitting sound to or from the diaphragm 105 of the enclosed electromagnetic unit 10. A clamping ring 129 and assembly screws 130 may be used to hold the aluminum plate 124 and the silk screen 123 in assembled relation on the open top of the insulating block 120, the assembly screws being arranged to pass through registering openings

provided in the clamping block, the aluminum plate 124 and the molded block 120.

In the event directional characteristics are to be imparted to the sound translating device, a cover casing member 13 is provided, as illustrated in Fig. 5 of the drawings, which comprises a block of acoustical insulating material 121. Preferably, the block 121 is formed by a molding process described more fully hereinafter and consists principally of a fibrous insulating material and a suitable binder; whereby the molded block 121 is of cellular construction and is somewhat porous so that air can be transmitted therethrough. The outer surfaces of the molded block 121 including the top wall and the connected side wall are provided with one or more coats of lacquer or paint 126 in order to minimize or substantially to exclude the transmission of sound therethrough. In the illustrated embodiment shown in Fig. 5 of the drawings, the molded block 121 may be either round or square in transverse cross-section in order to match the transverse cross-section of the molded block 120 illustrated in Fig. 1. The molded block 121 is provided with a number of sound transmitting passages 122 molded or cut therethrough along the axis of sound transmission to and from the diaphragm 105 of the associated electromagnetic unit 10. These passages are of the correct dimensions, that is, diameter and length, to provide for the desired sound energy transfer between the atmosphere and the acoustical cavity disposed adjacent the outer surface of the diaphragm 105. The molded block 121 may be secured to the molded block 120 to clamp the aluminum sheet 124 and the silk screen 123 to the open top of the molded block 120 by means of assembly screws 131 passed through registering openings in the two molded blocks 120 and 121.

In view of the foregoing description of the construction and arrangement of the electromagnetic unit 10 and the body casing member 11 of the sound translating device, it will be understood that a first acoustical chamber 117 is provided between the under side of the diaphragm 105 and the upper surface of the top plate 103; a second acoustical chamber 117a is provided between the upper side of the diaphragm 105 and the under surface of the aluminum plate 124; and a third acoustical chamber is formed by the wall structure of the molded block 120 itself. The third acoustical chamber formed by the wall structure of the molded block 120 itself is defined between the outer side walls of the annular permanent magnet 100, the outer bottom wall of the bottom plate 104, the under surface of the aluminum plate 124 and the outside coating of lacquer 125. Accordingly, the third acoustical chamber is of cellular construction, being entirely filled with the fibrous material of which the block 120 is molded.

The third acoustical chamber has a total volume determined by the exterior dimensions of the molded block 120 and the exterior dimensions of the electromagnetic unit 10, that is, the wall space of the molded block 120 between the exterior surface of the unit 10 and the interior surface of the coating of lacquer 125. However, the effective volume of the third acoustical chamber is determined in accordance with the density of the fibrous material of which the block 120 is molded, which in turn determines the porosity of the cellular structure thereof. Thus, it will be understood that, by varying the dimensions of the molded block 120 and consequently the total volume of the third acoustical chamber and also 75 by varying the density of the fibrous material of

which the block 120 is molded and consequently the effective volume of the third acoustical chamber, the characteristic of the third acoustical chamber may be determined. More specifically, the variation of the two factors mentioned above establishes the effective volume of the third acoustical chamber and consequently the mass and stiffness of the air entrapped in the cellular structure thereof, as well as the damping characteristic of the third acoustical chamber upon the diaphragm 105.

Finally it is noted in this connection that the third acoustical chamber of cellular construction communicates both with the first and second acoustical chambers, whereby the first and second acoustical chambers respectively disposed below and above the peripheral edge of the diaphragm 105 are interconnected by a controlled passage; the controlled passage constituting the fibrous or cellular wall structure of the molded block 120 extending below and above the peripheral edge of the diaphragm 105. Accordingly, the character of the third acoustical chamber determines the amount of damping which is exerted upon the passage of air between the first and second chambers through the wall structure of the molded block 120 incident to the vibration of the diaphragm 105.

Also it will be understood that the sound translating device comprises a fourth acoustical chamber which is formed by the wall structure of the cover casing member 13, whereby the sound transmitting passages 122 formed in the molded block 121 communicate both with the second acoustical chamber and the fourth acoustical chamber. More particularly, the fourth acoustical chamber is formed by the wall structure of the molded block 121 itself, as noted above, and is defined between the upper surface of the aluminum plate 124 and the outside coating of lacquer 126. Accordingly, the fourth acoustical chamber is of cellular construction, being entirely filled with the fibrous material of which the block 121 is molded.

The fourth acoustical chamber has a total volume determined by the exterior dimensions of the molded block 121 and the dimensions of the sound transmitting passages 122 formed therein. However, the effective volume of the fourth acoustical chamber is determined in accordance with the density of the fibrous material of which the block 121 is molded, which in turn determines the porosity of the cellular structure thereof. Thus it will be understood that, by varying the dimensions of the molded block 121 and consequently the total volume of the fourth acoustical chamber and also by varying the density of the fibrous material of which the block 121 is molded and consequently the effective volume of the fourth acoustical chamber, the characteristic of the fourth acoustical chamber may be determined. More specifically, the variation of the two factors mentioned above establishes the effective volume of the fourth acoustical chamber and consequently the mass and stiffness of the air entrapped in the cellular structure thereof, as well as the damping characteristic of the fourth acoustical chamber upon the diaphragm 105.

In the design of the sound translating device it will be understood that the third acoustical chamber may exhibit a considerable damping action upon the diaphragm 105 in the band of frequencies, including the resonant or natural frequency of the diaphragm 105, and may also

exhibit a considerable resonance action at a higher frequency above the resonant or natural frequency of the diaphragm 105. Similarly, the fourth acoustical chamber may exhibit a slight damping action upon the diaphragm 105 in the band of frequencies, including the resonant or natural frequency of the diaphragm 105, and may also exhibit a considerable resonance action at a still higher frequency above the resonance of the third acoustical chamber. This design of the sound translating device with particular reference to the characteristics of the third and fourth acoustical chambers is productive of a considerably extended and very flat response characteristic.

Referring now more particularly to Fig. 6 of the drawings, a modified form of the sound translating device is shown which is of the electrodynamic type and comprises a self-contained electromagnetic unit 20. Preferably, the unit 20 is identical to the unit 10 previously described. Also this sound translating device comprises a diaphragm 205 which embodies the same general construction as that previously described in connection with Fig. 3 if the device is to be used as a transmitter, and which embodies the same general construction as that previously described in connection with Fig. 4 if the device is to be used as a receiver. More particularly, the diaphragm assembly comprises an annular ring 206 formed of aluminum or the like to which the diaphragm 205 is suitably secured. Also the device comprises a body casing member 21 including a lower cup-shaped element 22 and two ring-shaped elements 23 and 24 arranged in stacked relation, the ring-shaped element 23 being positioned upon the rim of the cup-shaped element 22 and the ring-shaped element 24 being positioned upon the ring-shaped element 23. The body casing member 21 has the form of a hollow block of acoustical insulating material; the electromagnetic unit 20 being arranged and snugly received within the opening formed in the hollow block 21. Preferably, the hollow block 21 is formed by a molding process described more fully hereinafter and consists principally of a fibrous insulating material and a suitable binder, whereby the molded acoustical block 21 is of cellular construction and is somewhat porous so that air can be transmitted therethrough. Also this device comprises a cover casing member 25 in the form of a block of acoustical insulating material and provided with a number of sound transmitting passages 207 molded or cut therethrough along the axis of sound transmission to and from the diaphragm 205 of the unit 20. Preferably, the block 25 is formed by a molding process described more fully hereinafter and consists principally of a fibrous insulating material and a suitable binder; whereby the molded block 25 is of cellular construction and is somewhat porous so that air can be transmitted therethrough.

The annular ring 206 carrying the diaphragm 205 is positioned on the upper surface of the ring-shaped element 24 and the block 25 is positioned upon the annular ring 206. Also a sheet of paper or the like 208 impregnated with lacquer or paint is interposed between the cup-shaped element 22 and the ring-shaped element 23; and a sheet of paper or the like 209 impregnated with lacquer or paint is interposed between the two ring-shaped members 23 and 24. The body casing member 21 and the cover casing member 25 are retained in assembled relation by a number of assembly screws 210 extending through aligned openings provided therein, the outer ends of the

assembly screws 210 being threaded and carrying suitable nuts 211. The outer surfaces of the molded block 21 including the bottom wall and the connected side wall, as well as the outer surfaces of the molded block 25 including the top wall and the connected side wall, are provided with one or more coats of lacquer or paint 212 in order to minimize or substantially to exclude the transmission of sound therethrough. The molded blocks 21 and 25 may be either round or square in transverse cross-section in the illustrated embodiment shown in Fig. 6. The passages 207 provided in the block 25 are of the correct dimensions, that is diameter and length, to provide for the desired sound energy transfer between the atmosphere and the acoustical cavity disposed adjacent the outer surface of the diaphragm 205.

In view of the foregoing description of the construction and arrangement of the electro-magnetic unit 20 and the body casing member 21 of the sound translating device, it will be understood that a first acoustical chamber 213 is provided between the under side of the diaphragm 205 and the upper surface of the associated top plate 203; a second acoustical chamber 214 is provided between the upper side of the diaphragm 205 and the under surface of the molded block 25; a third acoustical chamber is formed by the wall structure of the ring-shaped element 24 itself; and a fourth acoustical chamber is formed by the wall structure of the ring-shaped element 23 itself. The third acoustical chamber formed by the wall structure of the molded ring-shaped element 24 itself is defined between the under side of the annular ring 206, the upper side of the impregnated sheet 209 and the outside coating of lacquer 212; while the fourth acoustical chamber formed by the wall structure of the molded ring-shaped element 23 itself is defined between the under side of the impregnated sheet 209, the upper side of the impregnated sheet 208 and the outside coating of lacquer 212. Accordingly, the third and fourth acoustical chambers are of cellular construction, being entirely filled with the fibrous material of which the respective ring-shaped elements 24 and 23 are molded.

The third acoustical chamber has a total volume determined by the exterior dimensions of the molded ring-shaped element 24; however, the effective volume of the third acoustical chamber is determined in accordance with the density of the fibrous material of which the ring-shaped element 24 is molded, which in turn determines the porosity of the cellular structure. Thus it will be understood that, by varying the dimensions of the molded ring-shaped element 24 and consequently the total volume of the third acoustical chamber and also by varying the density of the fibrous material of which the ring-shaped element 24 is molded and consequently the effective volume of the third acoustical chamber, the characteristic of the third acoustical chamber may be determined. More specifically, the variation of the two factors mentioned above establishes the effective volume of the third acoustical chamber and consequently the mass and stiffness of the air entrapped in the cellular structure thereof, as well as the damping characteristic of the third acoustical chamber upon the diaphragm 205.

The fourth acoustical chamber has a total volume determined by the exterior dimensions of the molded ring-shaped element 23; however, the effective volume of the fourth acoustical chamber is determined in accordance with the density of

the fibrous material of which the ring-shaped element 23 is molded, which in turn determines the porosity of the cellular structure thereof. Thus it will be understood that, by varying the dimensions of the ring-shaped element 23 and consequently the total volume of the fourth acoustical chamber and also by varying the density of the fibrous material of which the ring-shaped element 23 is molded and consequently the effective volume of the fourth acoustical chamber, the characteristic of the fourth acoustical chamber may be determined. More specifically, the variation of the two factors mentioned above establishes the effective volume of the fourth acoustical chamber and consequently the mass and stiffness of the air entrapped in the cellular structure thereof, as well as the damping characteristic of the fourth acoustical chamber upon the diaphragm 205.

Further it is noted in this connection that the first acoustical chamber 213 communicates with both the third and fourth acoustical chambers of cellular construction, whereby the third and fourth acoustical chambers commonly communicating with the first acoustical chamber 213 are interconnected by a controlled passage; the controlled passage including the fibrous or cellular wall structure of the molded ring-shaped elements 24 and 23. Accordingly, the characters of the third and fourth acoustical chambers determine the amount of damping which is exerted upon the passage of air from the first acoustical chamber 213 through the wall structures of the molded ring-shaped elements 24 and 23 incident to the vibration of the diaphragm 205. Preferably, the ring-shaped elements 23 and 24 are formed of fibrous material of different densities, whereby the third and fourth acoustical chambers exhibit different amounts of damping upon the passage of air to and from the first acoustical chamber 213 incident to the vibration of the diaphragm 205.

Also it will be understood that the sound translating device comprises a fifth acoustical chamber which is formed by the wall structure of the cover casing member 25, whereby the sound transmitting passages 207 formed in the molded block 25 communicate both with the second acoustical chamber 214 and the fifth acoustical chamber. More particularly, the fifth acoustical chamber is formed by the wall structure of the molded block 25 itself, as noted above, and is defined between the upper surface of the annular ring 206 and the outside coating of lacquer 212. Accordingly, the fifth acoustical chamber is of cellular construction, being entirely filled with a fibrous material of which the block 25 is molded.

The fifth acoustical chamber has a total volume determined by the exterior dimensions of the molded block 25 and the dimensions of the sound transmitting passages 207 formed therein. However, the effective volume of the fifth acoustical chamber is determined in accordance with the density of the fibrous material of which the block 25 is determined, which in turn determines the porosity of the cellular structure thereof. Thus it will be understood that, by varying the dimensions of the molded block 25 and consequently the total volume of the fifth acoustical chamber and also by varying the density of fibrous material of which the block 25 is molded and consequently the effective volume of the fifth acoustical chamber, the characteristic of the fifth acoustical chamber may be determined. More specifically, the variation of the two factors men-

tioned above establishes the effective volume of the fifth acoustical chamber and consequently the mass and stiffness of the air entrapped in the cellular structure thereof, as well as the damping characteristic of the fifth acoustical chamber upon the diaphragm 205. Finally it is pointed out that the sound translating device comprises a further sealed chamber which is formed by the wall structure of the cup-shaped element 22. The last-mentioned sealed chamber formed by the wall structure of the molded cup-shaped element 22 itself is defined between the outer walls of the electromagnetic unit 20, the under surface of the impregnated sheet 208 and the outside coating of lacquer 212. The last-mentioned chamber is substantially sealed from the fourth acoustical chamber of cellular construction formed by the molded ring-shaped element 23 due to the imposition of the impregnated sheet 208 between the molded cup-shaped element 22 and the molded ring-shaped element 23 and the snug fit of the electromagnetic unit 20 in the opening provided in the body casing member 21.

In the design of the sound translating device, it will be understood that the third and fourth acoustical chambers may exhibit different and considerable damping actions upon the diaphragm 205 in the band of frequencies, including the resonant or natural frequency of the diaphragm 205, and may also exhibit different and considerable resonance actions at two adjacent higher frequencies above the resonant or natural frequency of the diaphragm 205. Similarly, the fifth acoustical chamber may exhibit a slight damping action upon the diaphragm 205 in the band of frequencies, including the resonant or natural frequency of the diaphragm 205, and may also exhibit considerable resonance action at a still higher frequency above the resonances of the fourth and fifth acoustical chambers. This design of the sound translating device with particular reference to the third, fourth and fifth acoustical chambers is productive of a considerably extended and very flat response characteristic.

Consider now the process by means of which the blocks 120 and 121 in the first form of the sound translating device and the blocks 21 and 25 in the second form of the sound translating device may be molded. A mold of the required configuration is first selected, having given volumetric dimensions. The fibrous material utilized is of the rock-wool type and may comprise the material of which the air-acoustic sheets sold commercially under the trade name Johns-Manville are made. This rough fibrous material is thoroughly mixed with a suitable working agent, such as acetone, and a suitable binder, such as the cement sold under the trade name Ducco cement, in order to form a fairly smooth mixture in the general form of a plaster. A batch of the prepared plaster is then poured into the mold and allowed to set, whereby the acetone evaporates and the Ducco cement binds the fibrous material into a block having a cellular construction and being rather porous having a rather low density. After the block has set, it is removed from the mold and the outside surfaces thereof are covered or painted with a suitable lacquer in order to provide an outer shell which greatly minimizes or substantially prevents the passage of air and sound therethrough to the atmosphere. The thickness of the coating of lacquer on the outer surface of the block is determined in accordance

with the degree to which it is desirable to exclude the passage of air and sound through the block to the atmosphere. In the event a rather thick coating of lacquer on the outer surface of the block is desired, it may be obtained by first wrapping the outer surface with a thin layer of adhesive or masking tape and then spraying the tape with a heavy coating of lacquer.

In producing a sound translating device, a body casing member and a cover casing member, in the event the latter casing member is required, are suitably molded in the manner explained above, and an electromagnetic unit 10 of the required character is assembled in the manner previously explained. The unit is then assembled in the body casing member and the cover casing member is then assembled thereon in the event it is required. The assembly is then completed by suitably securing together the unit, the body casing member and the cover casing member. The completed assembly is then mounted upon a support utilizing clamps or the like engaging the body casing member and anchored to the support. Then the assembled and mounted sound translating device is tested in order to determine the operating characteristic thereof.

In the event the operating characteristics are not those desired, the necessary changes in the body casing member and in the cover casing member are made. For example, a new body casing member and a new cover casing member may be molded, having smaller or larger dimensions and molded of fibrous material of the same density. On the other hand, a new body casing member and a new cover casing member may be molded, having the same dimensions but comprising fibrous material of lesser or greater density. The new body casing member and the new cover casing member are then assembled with respect to the electromagnetic unit, and the sound translating device is again tested in order to determine the operating characteristic thereof. The above-described method is repeated until a sound translating device having the required operating characteristics is produced.

In placing in service a sound translating device having the desired operating characteristics and produced by the method described above, preferably, a supporting clamp or the like is utilized which engages the body casing member of the device and is anchored to the external support. This arrangement positively prevents the transmission of sound as well as vibration between the sound translating device and the support in view of the fact that the body casing member of the device is rather resilient and constitutes a sound and vibration insulator between the electromagnetic unit of the device and the external support. Hence, this arrangement insulates the diaphragm of the electromagnetic unit of the device from undesirable sounds which would otherwise be transmitted thereto from the external support through the supporting structure.

In view of the foregoing considerations it is apparent that there are provided an improved sound translating device, an improved method of making a sound translating device, and an improved process of molding an acoustical casing for a sound translating device.

While there have been disclosed what are at present considered to be the preferred embodiments of the invention, it will be understood that various modifications may be made therein which

are within the true spirit and scope of the invention.

What is claimed is:

1. A sound translating device comprising an electromagnetic unit including a vibratory diaphragm and structure cooperating with said diaphragm to define an acoustic cavity between said diaphragm and said cooperating structure, a hollow casing formed of a plurality of sections of cellular material of different densities engagingly surrounding and resiliently supporting said structure, and an outer shell substantially impervious to air surrounding said casing and cooperating with said structure to define a plurality of cellular cavities between said outer shell and said structure respectively housing the sections of said casing, said cellular cavities communicating with said acoustic cavity, whereby said cavities mutually influence the response of said diaphragm.

2. A sound translating device comprising an electromagnetic unit including a vibratory diaphragm and structure cooperating with said diaphragm to define an acoustic cavity between said diaphragm and said cooperating structure, a hollow self-supporting casing molded in a plurality of sections of cellular material of different densities, said casing engagingly surrounding and resiliently supporting said structure, and an outer

coating on said casing, said coating providing an outer shell substantially impervious to air and cooperating with said structure to define a plurality of cellular cavities between said outer shell and said structure respectively housing the sections of said casing, said cellular cavities communicating with said acoustic cavity, whereby said cavities mutually influence the response of said diaphragm.
